UNITED STATES PATENT OFFICE.

CHESTER R. KRANZ, OF CHICAGO HEIGHTS, ILLINOIS, ASSIGNOR TO AMERICAN Manganese STEEL COMPANY, OF CHICAGO, ILLINOIS, A CORPORATION OF MAINE.

RENEWABLE-CROWN BEATER BED.

Application filed October 9, 1924. Serial No. 742,525.

The improvements involved in the present invention are in the art of paper making, and particularly that part of the paper making process which has to do with the disintegration of rags or other material in the preparation of stuff from which the pulp is to be produced. The invention resides in an improved construction of bed which cooperates with the rotary beater for the purpose stated, and has for its object to provide a construction of beater bed which will permit of renewal of a portion of the bed as it wears out, without the necessity of discarding the whole of the body portion of the bed which is usually a substantial metallic mass of considerable cost, and, incidentally, if made separately and apart from the crown or wearing portion, can be produced of relatively less expensive metal than the crown. Accordingly, the invention consists in forming the beater bed for a machine of substantially the character referred to, of a body portion adapted to be supported in the machine in the usual way, or some other suitable manner, and a crown or top portion separately formed and designed to be mounted upon the body portion through means which enables the body portion to not only support it but to interlock with it and hold it against displacement in any direction; and, in short, to make the assembled body portion and top or crown a unitary structure that is functionally the equivalent of the single piece beds heretofore employed. The top or crown embodies the teeth, ribs, or other formation which render the bed effective in the service for which it is intended, thus economizing in the cost of maintenance of the bed, and rendering it economically practicable to produce the effective part of the bed of more durable material, such as manganese steel.

In order that the invention may be fully understood, several embodiments thereof are shown in the accompanying drawings, in which—

Figure 1 is an end elevation of a beater bed embodying one form of the invention.

Figures 2 and 3 are, respectively, a plan view and a side elevation of the same; and

Figures 4 to 9, inclusive, are vertical transverse sectional views showing various methods of holding the crown or renewable portion of the bed in assembly with the base or bed proper.

Referring to Figures 1 to 3, A represents a body portion or bed proper, the lower portion of which is of conventional design to adapt it to be mounted upon a known construction of beating engine. This body, according to the present invention, is constructed with a longitudinal ridge A' extending substantially throughout the length of the body A, and leaving on either side thereof shoulders A². B represents a crown corresponding in horizontal dimensions, approximately, to the body A, constructed with depending flanges B' which adapt the crown to rest astride of the rib A', and to be confined against transverse displacement relatively thereto after the manner of a saddle. The crown B may rest upon the body A through either its under face B² or by stepping flanges B' upon the shoulders A², or through both said means. In order to secure the saddle against vertical or longitudinal displacement on the body A, it is connected with the ridge A' through some suitable means, such, for instance, as bolts C passing through one of the flanges B', then through the ridge A', and then through the other flange B', and receiving a nut C' upon its inserted end.

As shown in Figure 2, the crown B may be subdivided transversely into sections, and these sections may meet through straight transverse faces to form a joint B³, or through staggered faces to form the joint B⁴, or through faces inclined to the longitudinal axis of the structure to form the joint B⁵.

Various means may be employed for preventing vertical and longitudinal displacement of the crown B relatively to the body A. For instance, as shown in Figure 4, this may consist of a wedge bolt D fitted to tapered bores through the crown flanges B' and the ridge A', and drawn to a firm seating by means of the bolt D'. Or, as shown in Figure 5, this may be accomplished by having a bolt E passed vertically through the crown B and the ridge A' and secured by countersunk nut E'. Or, as shown in Figure 6, the elements A and B may be secured together by means of clamp screws F. Or, as shown in Figure 7, the members A and B may be united by sliding them longitudinally one upon the other to bring into engagement tongues and grooves G and thus develop a so-called T-head joint. Or,

as shown in Figure 8, connection can be made by means of dovetail tongue and groove joint H. Or, as shown in Figure 9, the parts can be removably united by means 5 of poured molten metal keys I.

With all the illustrated forms of the invention, when the operative portion of a beater bed becomes worn, broken, or otherwise impaired, it is merely necessary to release the securing means and remove and replace the worn portion. Such a method of maintaining beater beds results in a great saving of metal as well as time required in restoring worn beater beds to serviceable 10 condition. The several methods of assembling the crown with the body block all involve firm vertical support and transverse interlock in the formation of the two members themselves, in addition to the bolting 15 or other securing means, and adapt the crown to withstand the forces which it encounters in use. Thus in all embodiments of the invention, the crown and body are interlocked together to form in effect a 20 structure that is single and unitary when in use, but separable to render one of its members replaceable when necessary.

While but one particular design of beater bed working surface has been illustrated, it 25 is to be understood that the invention applies to any known form of such machine element.

I claim:

1. In a beater engine, a beater bed comprising a base block constructed with a ridge, and a wearing crown carrying members through which the beater bed coacts with the beater; said crown being adapted to rest upon said ridge and having flanges 30 through which it embraces said ridge laterally, and releasable means being provided for securing said crown to said base.
2. In a beater engine, a beater bed com-

prising a base block constructed with a longitudinal upstanding ridge, and a crown 45 constructed with members for coacting with the beater of the engine and with the depending flanges, through which it embraces said ridge, means being provided for interlocking the flanges with the ridge.

3. In a beater engine, a beater bed comprising a base block constructed with a longitudinal upstanding ridge, and a crown constructed with members for coacting with the beater of the engine and with the depending flanges through which it embraces 50 said ridge, means being provided for interlocking the flanges with the ridge comprising means extending from the flanges into the ridge.

4. In a beater engine, a beater bed comprising a base block constructed with a longitudinal upstanding ridge, and a crown constructed with members for coacting with the beater of the engine and with the depending flange, through which it embraces 55 said ridge, means being provided for interlocking the flanges with the ridge comprising a bolt passing through both flanges and the intervening ridge.

5. In a beater engine, a beater bed comprising a base block having a ridge, and a crown having flanges depending on opposite sides of said ridge and engaging said ridge through tongue and groove construction.

6. In a beater engine, a beater bed comprising a base block having a ridge, a crown having flanges depending on opposite sides of said ridge and engaging said ridge through tongue and groove construction, 70 and a bolt passing through said flanges and ridge.

Signed at Chicago Heights, Illinois, this 30th day of September, 1924.

CHESTER R. KRANZ.
